UNITED STATES PATENT OFFICE.

GEORGE WHIGELT, OF DONGON HILLS, NEW YORK.

DEVICE FOR MIXING MATERIALS.

1,381,686.

Specification of Letters Patent. Patented June 14, 1921.

Application filed July 7, 1920. Serial No. 394,475.

To all whom it may concern:

Be it known that I, GEORGE WHIGELT, a citizen of the United States, and resident of Dongon Hills, in the county of Richmond 5 and State of New York, have invented a certain new and useful Device for Mixing Materials, of which the following is a specification, the same being a full, clear, and exact description of the invention, such as will 10 enable others skilled in the art to which it appertains to make and use the same.

This invention relates to apparatus for mixing liquid or semi-liquid material, as paste, paint, calcimine, color, filler, or similar substances of this type in which the mechanism is adapted for use with, and capable for application to, an ordinary receptacle, as a bucket or other container, and it has for 15 one object to provide a mechanically operated device which is readily adaptable either for permitting heavy material to be slowly mixed or agitated, or for causing light material to mix or agitate faster, or at a greater rate of speed.

Another object of the invention comprises 20 the use of a detachable propeller so that differently proportioned propellers may be substituted one for the other and the device consequently used with receptacles of various dimensions.

A further object is to provide a mechanically operated device which is readily portable, and which is simple in structure and efficient in operation.

With these and other novel and useful objects and purposes, which will be described below, the invention consists in the construction, arrangement and operation of parts hereinafter set forth and shown in the 35 drawing in which Figure 1 is an elevation of the invention, and Fig. 2 a plan view of my propeller.

Referring specifically to the drawing which represents an elevation of a device 40 constructed according to, and embodying one example of, my invention, the reference numeral 1 denotes an upright standard mounted on a suitable base 2. The upper portion or arm 3 of the standard extends 45 horizontally over the base, the standard also having a preferably horizontal bracket 4 positioned beneath the arm 3, the latter two parts being preferably connected by a suitable device as a post 5.

Above the free end of the arm 3 is preferably positioned a threaded fastening ele-

ment 17. In the free ends of the arm 3 and bracket 4 are formed bearings for a vertical rod 8 having keyed to the latter respectively large and small bevel gears 9 and 10, the said gears being adjustably held to the rod 8 by screws 7 carried by the hubs 6 of said gears, the height of the rod, and the propeller 12 carried by the same, as regards the base, being adjustably regulated by the 60 adjusting device 7.

In the standard 1 and post 5 are formed bearings respectively for the shafts 13 and 14 which respectively carry fixed bevel gears 15 and 16 which are constructed and arranged to mesh with the adjustable bevel gears 9 and 10. The gear 15 is preferably made of a comparatively large size and cooperates and coacts with the small gear 10, while the gear 16 is respectively smaller in 70 size and cooperates and coacts with the gear 9 which is preferably larger in diameter than the gear 10.

The shafts 13 and 14 are preferably constructed and arranged to be alternately operated by suitable means, such for example, for large power actuated apparatus, by pulleys as ordinarily employed for that purpose, or, in small portable devices, by manually actuated means, as in the present instance by the employment of a crank 17.

When it is desired to permit heavy material slowly to mix and agitate, I preferably operate the shaft 14 by the crank 17, whereby the gear 16 will operate the gear 9 80 at a comparatively slow speed. When, however, it becomes desirable to mix the body of material in the receptacle 19 at a greater rate of speed, or when it is deemed advantageous to permit light material to mix or 85 agitate faster, I operate the shaft 13 by the crank 17, whereby the small gear 10 of the rod 8 will be caused to rotate at a higher rate of speed by means of its coöperation or coaction with the relatively larger gear 15, by 90 which arrangement the propeller 18 may be rotated at different rates of speed by operating the fixed gears 13 and 14 alternately.

It will be noted that when one fixed gear, as the gear 16, is rotated, its coacting adjustable gear 9 on the rod 8 will rotate and operate in unison therewith, while the other adjustable rod gear 10 will rotate its coacting fixed gear 15 at a different and lower rate of speed, the latter then serving to steady 100 the motion of the first named rod gear. The increased mixing power of my device saves 110

enough time and energy over methods heretofore used to commend itself to all users of such devices, while when in continuous use with materials of differing character it 5 requires only the cleaning of the propeller, besides which it permits the use of a receptacle 19 from which the mixed material may be taken and directly applied as desired, thus obviating the necessity for a special 10 mixing receptacle specially adapted for its particular mixing device.

I wish it to be understood that I do not desire to be limited to the particular use or the exact details of construction shown and described, for obvious modifications will occur 15 to persons skilled in the art.

What I claim as my invention is:—

1. In a device of the class described, a stand, a rod supported thereby in a movable 20 relation, relatively large and small gears mounted on the rod, a shaft carrying a small gear to mesh with the said large gear, a shaft carrying a large gear to mesh with the first named small one, and means to operate either 25 shaft at will.

2. In a device of the class described, a stand, a rod supported thereby in a movable relation, relatively large and small adjustable 30 gears mounted on the rod, a shaft carrying a fixed small gear to mesh with the said large

gear, a shaft carrying a fixed large gear to mesh with the first named small one, and means to operate either shaft at will.

3. In a device of the class described, a stand, a rod supported thereby in a movable 35 relation and adjustable in height thereon, means to hold the rod in adjusted position, respectively large and small gears encircling the rod, means on the stand to hold said gears in their operative vertical positions, a shaft 40 carrying a small gear to mesh with the said large one, a shaft carrying a large gear to mesh with the first named small one, and means to operate either shaft at will.

4. In a device of the class described, a stand, a rod supported thereby in a movable 45 relation, relatively large and small adjustable gears mounted on the rod, a shaft carrying a fixed small gear to mesh with the said large gear, a shaft carrying a fixed large gear to 50 mesh with the first named small one, and means to operate either shaft at will, and also means to operate either fixed gear and its co-acting gear on the rod, whereby the other gear on the rod will rotate its co-acting fixed 55 gear at a different rate of speed, the latter serving to steady the motion of the first named rod gear.

GEORGE WHIGELT.
